UNITED STATES PATENT OFFICE.

FREDERICK W. LOVELL, OF CLEVELAND, OHIO, ASSIGNOR TO THE McMYLER INTER-STATE COMPANY, OF CLEVELAND, OHIO, A CORPORATION OF OHIO.

CAR-HAULAGE PLANT.

1,125,354.

Specification of Letters Patent. Patented Jan. 19, 1915.

Application filed September 27, 1913. Serial No. 792,105.

To all whom it may concern:

Be it known that I, FREDERICK W. LOVELL, a citizen of the United States, residing at Cleveland, in the county of Cuyahoga and 5 State of Ohio, have invented a certain new and useful Improvement in Car-Haulage Plants, of which the following is a full, clear, and exact description.

This invention relates to car haulage 10 plants of the general type used in connection with the various kinds of car handling apparatus, such as car dumpers.

At the present time, loaded cars are brought up onto the cradle of a car dumper, 15 the approach to the car dumper being usually upwardly inclined, by a haulage car adapted to be moved by a suitable haulage cable along a narrow gage haulage track arranged between the rails of the main track 20 and terminating in a pit arranged a suitable distance in advance of the car dumper approach. The haulage car is run into the pit when it is desired that a loaded car be moved forward to a point in advance thereof, so that when the haulage car is removed 25 from the pit, it will be at the rear of and can thence push the car up onto the cradle of the car dumper. This system while satisfactory in some respects, does not admit of 30 the most advantageous handling of the cars, for it is obvious that a loaded car can not be spotted, that is, brought to a position in advance of the pit, until after the haulage car is in the pit. It is especially disadvan- 35 tageous in those systems wherein the loaded cars are run by gravity down an inclined portion of the track to the base of the car dumper approach, for the reason that it is often the case that the cars cannot be 40 stopped on the incline in their descent until after they pass the pit. Hence, it is necessary, or at least advisable, to start a car down the incline only after the haulage car is in the pit. This results in loss of time in 45 the shifting of the cars.

The object of the present invention is to provide a haulage system which will enable the cars to be handled in a more economical manner, and in such a way as to avoid the 50 delays incident to the shifting of the cars, with the haulage plants generally in use at the present time.

In the car haulage plant which I have devised, a haulage track is located adjacent 55 and preferably beneath the main track, and

the haulage car is provided with a movable pusher device or arm which can be moved to a position such as to engage an appropriate part of the car to be moved, or can be swung to another position such that the haulage car 60 as a whole may pass a car standing on the main track.

The present invention resides particularly in means for shifting or controlling the movement of the pusher device or arm, and 65 in the general arrangement of parts by which the objects of this invention are attained.

My invention may be further briefly summarized as consisting in certain novel details of construction and combinations and arrangements of parts which will be described in the specification and set forth in the appended claims.

In the accompanying sheets of drawings, 75 wherein I have shown one embodiment of my invention adapted to be employed in connection with a car dumper, Figure 1 is a side view on a reduced scale, showing the approach to a car dumper and a portion of the 80 track leading thereto, and showing also the haulage car in the act of moving a car up along said car dumper approach; Fig. 2 is a plan view on an enlarged scale showing a portion of the main track, a portion of the 85 haulage car track, and the haulage car embodying my invention; Fig. 3 is a partial longitudinal sectional view substantially along the line 3—3 of Fig. 2, showing the haulage car in side elevation with the tilt- 90 able arm elevated to operable position, and showing by dotted lines the arm in its lowered position, or in the position which it occupies when the haulage car is moving rear- 95 wardly; Fig. 4 is a transverse sectional view through the main track, haulage track and haulage car substantially along the line 4—4 of Fig. 3; Fig. 5 is a transverse sectional view through the haulage car substantially along the line 5—5 of Fig. 3, looking in the 100 direction indicated by the arrow.

In the drawings, 10 is an elevated and inclined track which may be the inclined approach to a car dumper which is not shown. At the base of the inclined part 10 there is 105 a short horizontal section 11 to which the cars may move by gravity down the inclined section 12 in a manner previously stated.

Arranged between the rails of the main track and a suitable distance below the same 110

are the rails of a narrow gage track 13 for the haulage car, this haulage track extending along and being parallel to the upwardly inclined and horizontal sections 10 and 11 of the main track. However, it is perhaps not essential that the haulage car track be throughout its length the same uniform distance below the main track, but it is essential that it be sufficiently below the main track that the haulage car with its pusher arm lowered may pass beneath and to the rear of the main car to be moved, at that part of the track where the main car will stand, after being brought to the position to be engaged and shifted by the haulage car.

The haulage car which is adapted to be run along the haulage car track, is designated as a whole by the reference character 14. This haulage car, as will be seen by reference to Figs. 2, 3, 4 and 5, includes a suitable frame 15 composed of longitudinal side members 16 and suitable cross members to be referred to presently, all of which may be formed of structural material, together with axles 17 supported in suitable bearings carried by the frame, and track wheels 17^a secured to the ends of the axles.

Depending from the side frame members 15 between the front and rear wheels and nearer the former than the latter, are bearing plates 18 in which is supported a short distance above the rails of the haulage track, a transversely extending shaft 19, on which is pivotally supported a rather long pusher arm or ram 20, which is supported near its rear end and projects forwardly beyond the forward end of the haulage car a considerable distance, as shown in several figures of the drawing. This arm 20 is mounted so that it may be swung upwardly to a position such that its forward end 21 will be at a suitable height to engage an appropriate part of the main car shown at 22, in Fig. 1, to be moved by the haulage car, and so that it may be swung downwardly to the position shown by dotted lines in Fig. 3, below the level of the main track or at least to a certain position with reference thereto, that the haulage car as a whole may move rearwardly or backwardly beneath the car 22 which is in position to be hauled up the inclined approach. The major portion of this arm 20 may be formed of structural material, as shown more particularly in Fig. 5, wherein it is shown as composed of side plates and top and bottom channels forming a hollow beam, and the rear end of the arm 20 is a counterweight 23, so arranged and of such size as to substantially counterbalance the weight of the forward end of the arm, the arm being thereby substantially balanced on the pivotal support 19. This arm 20 which is located and adapted to swing in the longitudinal center plane of the haulage car is guided at the forward end of

the latter by a pair of vertical parallel guide members 24, suitably supported from the side members of the main frame 15 and spaced apart so that the arm may move freely up or down between the same, but will nevertheless be prevented from having any material sidewise movement. At the rear end of the haulage car, the side members 16 of the car frame are connected together by suitable cross members 25 and at the forward end of the frame, the side members are connected together by a lower cross member 26, and by an upper arched cross member 27, the members 26 and 27 being so arranged or located that they will not interfere with the necessary swinging movement of the arm 20, either upwardly or downwardly. To limit the swinging movement of the arm in both directions, the front guides 24 are provided with forwardly projecting plates 28 provided with slots 29 into which project the ends of a cross member 30 secured to the pusher arm 20. The length of the slots is such as to permit the desired movement in either direction.

The car is adapted to be moved forwardly up the haulage track by hoisting mechanism, including a cable 31, which at its rear end is connected to links 32 mounted on the central part of the shaft 19, as shown particularly in Figs. 3 and 5. The cable extends forwardly up to and around a suitable sheave at the forward end of the haulage track, and thence in this case passes rearwardly around an idler sheave and to a drum on which the cable is adapted to be wound. In order that such a haulage car may be effectively used to haul a car up the track, I have provided mechanism which at the beginning of the forward movement of the car immediately swings the arm 20 to its upper position, and at the beginning of the rearward movement of the car immediately causes the arm to swing downward to its lower position. I accomplish this result in a very effective manner by friction mechanism actuated by the haulage car, and including two members 35 which are mounted on and frictionally engage a drum 36, which is secured to and rotates with the rear axle, this being shown most clearly in Fig. 4. These friction members 35 are pivotally connected together by a pin 36^a and diametrically opposite the pin, are pulled yielding toward each other and onto the drum by a spring 37, which surrounds a bolt passing through outstanding ears of the two members 35. Between the friction members 35 and the drum 36 is a suitable lining of asbestos or other suitable frictional material. In consequence, when the haulage car is moving forwardly, the friction members 35 will tend of course to rotate with the same, and turn in a counter-clockwise direction, as viewed in Fig. 3, but when the car is moved

rearwardly, these members tend to turn in a clockwise direction. In order that these friction members may be utilized to swing the arm upwardly or rearwardly, they are connected to the rear end of the counterweight by means of links 38, which are located alongside the counterweight and at their upper ends are pivotally connected to the latter, and at their lower ends are pivotally connected to the pin 36^a just referred to.

In the haulage plant arranged and constructed in accordance with my invention, the haulage car may run down the tracks and may pass beneath and to the rear of a car to be hauled up the inclined approach, the pivoted arm 20 then being of course lowered. However, when the haulage car is moved forwardly by the cable 28, the friction members 35 at first turn with the axle, and in consequence, pull downwardly the counterweight and swing the forward end of the arm 20 to upright position and maintain it in that position as long as the haulage car is moving forwardly, and until it starts in the reverse direction, for even though the car may be stopped, the arm will not swing downward until actual movement in a reverse direction is started. As soon, however, as the haulage car starts to move rearwardly, the arm swings to the position shown by dotted lines, or to the position such that the haulage car as a whole may pass beneath a car standing on the main track.

Having thus described my invention, what I claim is:

1. In a car haulage plant, a main track for a car to be moved, a haulage track adjacent the main track, a haulage car on said haulage track, a movable device carried by said haulage car and adapted to be moved to a position such that it will engage a car on the main track and to a position such that the haulage car as a whole may pass a car on the main track, means for moving the haulage car, and means carried by the haulage car for automatically shifting said device when the haulage car is moved.

2. In a car haulage plant, a main track for a car to be moved, a haulage track adjacent the main track, a haulage car on said haulage track, a movable device carried by said haulage car and adapted to be moved to a position such that it will engage a car on the main track and to a position such that the haulage car as a whole may pass a car on the main track, and means carried by the haulage car and controlled by the movement of the latter for shifting said device.

3. In a car haulage plant, a main track for a car to be moved, a haulage track adjacent the main track, a haulage car on said haulage track, a movable car pusher device carried by said haulage car and adapted to

be moved to a position such that it will engage a car on the main track, or to a position such that the haulage car as a whole may pass a car on the main track, and means comprising a friction device carried by the haulage car for shifting said device.

4. In a car haulage plant, a main track for a car to be moved, a haulage track adjacent the main track, a haulage car on said haulage track, a movable device carried by said haulage car and adapted to be moved to a position such that it will engage a car on the main track, or to a position such that the haulage car as a whole may pass a car on the main track, and means for shifting said device comprising a rotary part on the car and means frictionally engaging the same and operatively connected to said device.

5. In a car haulage plant, a main track for a car to be moved, a haulage track adjacent the main track, a haulage car on said haulage track, a movable device carried by said haulage car and adapted to be moved to a position such that it will engage a car on the main track, or to a position such that the haulage car as a whole may pass a car on the main track, a member operatively connected to said device for moving the same, and means on the car for automatically moving said member in one direction or the other, depending on the direction of movement of the car.

6. In a car haulage plant, a main track for a car to be moved, a track for a haulage car extending beneath the main track, a haulage car on said haulage track having a movable pusher arm adapted to move upwardly to a position to engage a car on the main track and to move downwardly so that said haulage car may pass beneath a car on the main track, means for moving the haulage car, and means carried by the haulage car for shifting the arm.

7. In a car haulage plant, a main track for a car to be moved, a track for a haulage car extending beneath the main track, a haulage car on said haulage track having a movable pusher arm adapted to move upwardly to a position to engage a car on the main track and to move downwardly so that said haulage car may pass beneath a car on the main track, and means carried by the haulage car and controlled by the direction of movement of the latter for shifting the pusher arm.

8. In a car haulage plant, a main track for a car to be moved, a track for a haulage car extending beneath the main track, a haulage car on said haulage track having a movable pusher arm adapted to move upwardly to a position to engage a car on the main track and to move downwardly so that said haulage car may pass beneath a car on the main track, and means comprising

ing a friction device carried by the car for shifting said pusher arm.

9. In a car haulage plant, a main track for a car to be moved, a track for a haulage car extending beneath the main track, a haulage car on said haulage track having a movable pusher arm adapted to move upwardly to a position to engage a car on the main track and to move downwardly so that said haulage car may pass beneath a car on the main track, and means for shifting said pusher arm comprising a rotary part on the car, and means frictionally engaging the same and operatively connected 15 to the pusher arm.

10. In a car haulage plant, a main track for a car to be moved, a track for a haulage car extending beneath the main track, a haulage car on said haulage track having 20 a movable pusher arm adapted to move upwardly to a position to engage a car on the main track and to move downwardly so that said haulage car may pass beneath a car on the main track, a member operatively connected to said pusher arm for mov- 25

ing the same, and means on the car for moving said member in one direction or the other, depending on the direction of movement of the car.

11. In a car haulage plant, a main track 30 for a car to be moved, a track for a haulage car beneath the same, a haulage car on said haulage track provided with a pivoted pusher arm projecting forwardly beyond the car and adapted to be swung upwardly into the path 35 of the car to be moved, or downwardly so that the pusher car may pass beneath the car to be moved, and means for swinging the arm upwardly or downwardly comprising a friction drum on one axle of the 40 pusher car, and a movable friction device surrounding the drum and having an operative connection with the arm.

In testimony whereof, I hereunto affix my signature in the presence of two witnesses. 45

FREDERICK W. LOVELL.
